(**) Term: **15 Years**

CLAIM

(21) Appl. No.: **29/716,059**

The ornamental design for a support for mobile phone and tablet personal computer, as shown and described.

(22) Filed: **Dec. 6, 2019**

DESCRIPTION

(51) LOC (13) Cl. **26-05**

FIG. 1 is a perspective view of a support for mobile phone and tablet personal computer in accordance with a first embodiment showing my new design;

(52) U.S. Cl.

FIG. 2 is a front elevational view thereof;

USPC **D26/74**

FIG. 3 is a rear elevational view thereof;

(58) **Field of Classification Search**

FIG. 4 is a left side elevational view thereof;

USPC D14/447, 432, 434, 439, 440, 451, 452,

FIG. 5 is a right side elevational view thereof;

D14/457, 239, 253; D8/363, 373, 380;

FIG. 6 is a top plan view thereof;

D6/406.3, 406.4, 406.5, 406.6; D12/415

FIG. 7 is a bottom plan view thereof;

CPC A47B 21/04; A47B 2097/006; A47B

FIG. 8 is a perspective view of the support for mobile phone and tablet personal computer in accordance with a second embodiment;

2097/005; A47B 2023/049; A45C

FIG. 9 is a front elevational view thereof;

2011/002; A45C 2011/003; F16M

FIG. 10 is a rear elevational view thereof;

2200/00; F16M 13/00

FIG. 11 is a left side elevational view thereof;

See application file for complete search history.

FIG. 12 is a right side elevational view thereof;

(56) **References Cited**

FIG. 13 is a top plan view thereof; and,

U.S. PATENT DOCUMENTS

FIG. 14 is a bottom plan view thereof.
